(57) **CLAIM**

The ornamental design for a striking tool, as shown and described.

DESCRIPTION

FIG. 1 is a first isometric view of a striking tool in accordance with a first embodiment of the present invention;

FIG. 2 is a second isometric view of the striking tool illustrated in FIG. 1;

FIG. 3 is a first side view of the striking tool illustrated in FIG. 1;

FIG. 4 is a rear elevation view of the striking tool illustrated in FIG. 1;

FIG. 5 is a second side view of the striking tool illustrated in FIG. 1;

FIG. 6 is a front elevation view of the striking tool illustrated in FIG. 1;

FIG. 7 is a top plan view of the striking tool illustrated in FIG. 1;

FIG. 8 is a bottom plan view of the striking tool illustrated in FIG. 1;

FIG. 9 is a first isometric view of a striking tool in accordance with a second embodiment of the present invention;

FIG. 10 is a second isometric view of the striking tool illustrated in FIG. 9;

FIG. 11 is a first side view of the striking tool illustrated in FIG. 9;

FIG. 12 is a rear elevation view of the striking tool illustrated in FIG. 9;

FIG. 13 is a second side view of the striking tool illustrated in FIG. 9;

FIG. 14 is a front elevation view of the striking tool illustrated in FIG. 9;

FIG. 15 is a top plan view of the striking tool illustrated in FIG. 9; and,

FIG. 16 is a bottom plan view of the striking tool illustrated in FIG. 9.

The broken lines in the figures show elements of the striking tool which form no part of the claimed design.
